UNITED STATES PATENT OFFICE.

EDWARD M. MARKHAM, OF WEST POINT, NEW YORK.

MAKING AND INSTALLING REVETMENT MATS.

Application filed December 30, 1916. Serial No. 139,940.

To all whom it may concern:

Be it known that I, EDWARD M. MARKHAM, of West Point, in the county of Orange and State of New York, have invented certain new and useful Improvements in Making and Installing Revetment Mats; and I do hereby declare the following to be a full, clear, and exact description of the invention, such as will enable others skilled in the art to which it appertains to make and use the same.

My invention relates to the art of constructing and depositing slabs or revetment sheets or mattresses to be used subaqueously for protecting the shores or base of running streams or any body of water against scour or erosion. It is a well recognized fact that the best protection against scour or erosion is a concrete mat, but the use of such mats where they are deposited in their entirety beneath the surface of the water has been attended with difficulty in launching them due to the fact that the mats are liable to pile up and crumple thus defeating the very purpose for which they are created, namely, revetting the bank or bed of the river or other body. This is especially true where operations are carried on on a major scale and mats containing many hundred square feet and weighing thousands of pounds are employed.

It is the object of my invention to provide an improved method of making and installing revetment mats and an improved and highly efficient mechanism for laying such mats, new and improved means being employed for controlling the mat after the barge upon which it has been constructed has been removed from beneath it, the controlling step insuring a uniform sinking of the mat, thus minimizing its distortion and preventing its lateral shift out of the proper line of direction.

In the accompanying drawings, Figure 1 is a view in side elevation of a mooring barge and the mat barge with one of the supporting trusses, the figure indicating the position of the parts in the first step, namely, with the mat formed upon the movable barge. Figures 2 and 3 are views similar to Figure 1 with the mat barge fully withdrawn and the mat held in suspended position, in Figure 2 about at the water line and in Figure 3 partially lowered. Figures 4 and 5 are longitudinal sectional views of a portion of the mat barge platform. Fig-

ure 6 is a cross sectional view of a portion of the mat barge platform showing one of the launching boards and a supporting roller. Figure 7 is a top plan view of a mat with guiding lines in position. Figure 8 is a view in perspective showing three trusses with their ends resting upon a portion of the mat barge.

In carrying out my invention I preferably employ a mooring barge 1 and a mat barge 2 upon which latter the mat is formed. The barge 2 has a slanting surface to facilitate its separation from the mat by sliding out beneath it. The mat formed of reinforced concrete is generally indicated at 3. It will be readily understood that the mat or slab is to be constructed upon the barge 2 and is to be installed upon the bed or bank of a river or other body of water to provide a protecting surface for the bank or bed or it may be used to protect any structure located within the water. By my improved method I provide for maintaining control of the mat during and after removal of the mat barge.

I employ a series of trusses 4, one only of which is shown in Figures 1, 2 and 3, while several are indicated in Figure 8. These trusses may be hinged to the mooring barge 1 and suitably supported as by lines 5 extending over an upright 6 and secured to the barge 1. Also secured to the barge 1 and extending vertically downward to the bed of the stream are spuds 7, although such spuds may be dispensed with if so desired. The trusses have wheels 8 to provide end bearings and to facilitate their movement over the mat barge as the latter recedes. On a shaft 9 extending through one of the truss frames is a series of winding drums 10 on which are wound chains or cables 12 suitably secured to the mat as at 13. These cables are preferably secured to the mat by any appropriate form of trigger or trip mechanism under the control of lines 14 by which they may be released.

The mat barge 2 may be moved in or out relative to the mooring barge by lines 15 passing through the end trusses over sheaves 17, and lines 16, the said lines 15 and 16 leading to power established on the mooring barge. The tension of these lines effects and controls desired movement of the mat barge, the lines 16 to maintain the mat barge in juxtaposition to the mooring barge and the lines 15 passing over the sheaves 17 on the

trusses to draw the mat barge away from the mooring barge and from beneath the greater portion of each truss.

Independently of supporting the weight 5 of the mat it is of primary importance that means be provided to prevent movement of the mat with the mat barge, racing off the latter, or shifting laterally while the mat barge is being moved from under it and 10 after the barge is completely removed. I provide against horizontal movement of the mat by lines 18 shown in the form of chains and as anchored to the barge 1, or by lines 18', also shown as chains, attached to trolleys 18² movable on spuds 7. These trolleys are arranged to hug the spuds 7 which form guiding members for the trolleys in their descent. Manifestly if the mat is to be guided by the trolleys the lines 18 are not 15 used. On the other hand the trolleys are not used if the mat is to be disconnected at the water level, the lines 18 being employed to prevent horizontal movement while the barge 2 is being withdrawn. A line or chain 20 19 connecting the mat to the superposed structures will prevent the said mat from racing off the barge during withdrawal of the latter. Lines 20 and 21 attached to opposite sides of the mat may be secured to 25 suitable anchorages to the end that the mat shall be restrained from undesired movement while in suspension or while being lowered or after being tripped from its overhead support.

30 35 If it be desired to lower the mat wholly to position its control may also be effected by lines 22, 23 attached to the mat at its opposite sides and passing over sheaves 24, 25, 26, 27 to drums 28 on the barge 1. These 40 drums are shown under control of a governor shown diagrammatically at 29 connected by lines 30, 31, to a hanger 32 through which passes the chain or cable 12'. Lateral movement of this cable, such as would result from 45 a shift of the mat, will swing the hanger and, through the links, will actuate the governor to turn the drum and thus recover or let out lines 22 or 23, with the result of maintaining the verticality of the supporting line 12.

50 It will be understood that the drums 28 and governor 29 are shown diagrammatically, the controlling lines 15, 16, 22, 23 being so led to and manipulated on the said 55 drums that, for instance, tension may be applied to the line 15 or 16 independently of the lines 22 and 23 and vice versa,—also that the movement or regulation of the position of the mat 3 is accomplished by the slackening 60 of 22 simultaneously with the hauling of line 23 and vice versa.

I also endeavor to minimize the friction occasioned by the mat sliding off the barge 2. For this purpose I may construct the 65 platform of the barge 2 in sections 35, 36,

Figure 6. These sections may be separated by ways 37 to receive rollers 38. Before forming the mat launching boards 39 may be placed upon the rollers. By means of liners, lifting jacks or other means the sections may be brought into position flush with the launching boards so that the mat may be built upon a uniform surface. After its formation the platform sections may be lowered away from the mat, leaving the 70 finished structure resting upon the launching boards, the ends of which are indicated in Figure 8. Thus the weight of the mat is distributed over the launching boards and in 75 turn upon the rollers 38.

A means of attaining the purpose of the construction just described is illustrated in Figures 4, 5 and 6. There the timbers 40, supporting the platform sections, are formed with recesses 41 and are movable independently of the platform sections over the rollers 42. By means of a wedge 43 these timbers 40 may be moved until their recesses are in alignment with the rollers when the platform sections will drop a distance corresponding to the depth of the recesses and thus be removed from contact with the mat.

From what has been said it will be apparent that the mat barge and the mooring barge are in juxtaposition at the first stage 95 of the method of preparing and laying revetment mats, being held in this position by the lines 16, with the outer ends of the trusses 4 at the highest point of the inclined surface of the mat barge. The concrete mat is then formed on this mat barge within the limits of the lower end of the barge platform and the point of engagement of the rollers 8 with the timbers which form the ways. In the formation of the mat the 100 cables 12 are secured to the reinforcing elements of the mat by a trigger mechanism shown at 13 and in such manner as to be tripped by the pulling action of lines 14. After the concrete has sufficiently set the 105 lines 15 are taken in through suitable power on the mooring barge, the lines 16 being slack. This effects the withdrawal of the mat barge. As the latter is withdrawn the 110 mat is held suspended by the trusses 4 through the chains or cables 12. When the barge is fully withdrawn from beneath the mat the ends of the trusses will still be supported on the barge. The mat may now 115 be lowered while still in suspended state and after it has reached a predetermined depth the lines 14 may be manipulated to release the connections between the lines 12 and the mat. Control of the mat during 120 the lowering operation is aided by the chains 18' connecting the mat with the trolleys on the spuds 7. It is understood that the mat may be disconnected from the supporting trusses at the water level or at any other 125 point and allowed to drop to position un-

aided by the chains and trolleys or other connecting lines.

I claim as my invention:

1. The herein described method of making and installing revetment mats consisting in forming a mat on a relatively movable base, bodily removing the base from beneath the mat, supporting the mat from above while the base is being removed and subsequently lowering the mat to position.

2. The herein described method of making and installing revetment mats consisting in forming the mat on a movable float, bodily removing the float from beneath the mat, supporting the mat above the proposed point of installation while the float is being removed and after it is separated from the mat, and subsequently lowering the mat to position.

3. The herein described method of making and installing revetment mats consisting in forming the mat on a movable float, bodily removing the float from beneath the mat, supporting the mat above the proposed point of installation while the float is being removed and after it is separated from the mat, and releasing the mat from the supporting means.

4. An apparatus for making and installing revetment mats including a mat barge having a plurality of sections and launching boards intermediate the sections, means for maintaining said sections flush with said launching boards while the mat is being formed, such means being adapted for actuation to move the sections out of contact with the mat to place the weight of the mat on the launching boards.

5. Mechanism for making and installing revetment mats comprising a mat barge, superposed trusses, a mat formed on said barge, supporting means suspended from said trusses and connected to said mat, means for tripping said supporting means, and means for withdrawing said barge from beneath said mat.

6. Mechanism for making and installing revetment mats comprising a mat barge, superposed trusses, rollers on said trusses and movable on said barge, a mat formed on said barge, supporting means suspended from said trusses and connected to said mat for temporarily supporting the mat, and means for withdrawing said barge from beneath said mat.

7. Mechanism for making and installing revetment mats comprising a mat barge, a mat formed on said barge, means for removing said barge from beneath said mat after its completion, means for supporting said mat after said barge is removed, means for tripping said last mentioned means, and means for preventing the lateral shift of said mat during its descent.

8. Mechanism for making and installing revetment mats comprising a mat barge, a mat formed on said barge, means for removing said barge from beneath said mat after its completion, means for temporarily supporting said mat after said barge is removed and during its lowering movement, and means for preventing the lateral shift of said mat while being lowered.

9. Mechanism for making and installing revetment mats comprising a mat barge, a mat formed on said barge, means for removing said barge from beneath said mat after its completion, means for temporarily supporting said mat after said barge is removed and during its lowering movement, and means for guiding said mat while being lowered, including downwardly extending relatively fixed members, trolleys movable along said members, and detachable chains connecting said mat and said trolleys.

10. An apparatus for laying a rigid revetment mat, comprising a barge adapted to support a concrete mat, a hoisting barge adjacent thereto, crane members extending from the hoisting barge over the mat, means for supporting the mat from the crane members and for withdrawing the barge from beneath the mat, means for lowering the mat, and separate means for simultaneously releasing it at all points.

11. An apparatus for laying a rigid revetment mat and means for placing it, comprising means for freely suspending the unit mat, said means comprising a supporting frame work, a plurality of separate supporting members arranged in parallel between the mat and the frame work, means for adjusting them to support the mat in its entirety above its position of rest, and means for simultaneously disconnecting all such members to cause the mat to drop freely as a unit toward its ultimate position.

12. An apparatus for laying a rigid revetment mat comprising a bed upon which the mat lies, a frame work above the mat, a plurality of separate supporting members arranged in parallel between the frame work and the mat, means for exerting a tension upon said members and adjusting them to support the mat in its entirety above its position of rest when the bed is withdrawn, means for withdrawing the bed and leaving the mat suspended by the supporting members, and means for simultaneously disconnecting all such members to cause the mat to drop freely toward its ultimate position.

13. An apparatus for laying a rigid revetment mat comprising a bed upon which the mat lies, a frame work above the mat, a plurality of separate supporting members arranged in parallel between the frame work and the mat, means for exerting a tension

upon said members and adjusting them to support the mat in its entirety above its position of rest when the bed is withdrawn, means for withdrawing the bed and leaving the mat suspended by the supporting members, and means for simultaneously controlling said supporting members to lower the mat as a unit toward its ultimate position.

10 14. An apparatus for laying a rigid revetment mat comprising a bed upon which the mat lies, a frame work above the mat, a plurality of separate supporting members arranged in parallel between the frame work and the mat, means for exerting a tension upon said members and adjusting them to support the mat in its entirety above its position of rest when the bed is withdrawn, means for withdrawing the bed and leaving the mat suspended by the supporting members, means for simultaneously controlling said supporting members to lower the mat as a unit toward its ultimate position, and means for simultaneously disconnecting all such supporting members to cause the mat to drop freely as a unit toward its ultimate position.

15 15. The method of placing rigid revetment mats which consists in first supporting the mat from below, then arranging for its suspension as a unit from above, then withdrawing the lower support, then lowering the mat as a unit toward its position of rest, then releasing all parts of the mat simultaneously and permitting it to drop as an uncontrolled unit toward its position of rest.

20 16. In an apparatus for laying a rigid revetment mat, a movable support adapted to support a mat from below, an additional support base, supports mounted thereon adapted to support the mat from above, and means for laterally moving the lower support from beneath the mat.

25 17. In an apparatus for laying a rigid revetment mat, a movable support adapted to support a mat from below, an additional support base, supports mounted thereon adapted to support the mat from above, and means for laterally moving the lower support from beneath the mat, the upper supports being provided with wheels and the lower support with tracks to support them.

30 18. In an apparatus for laying a rigid revetment mat, a movable support adapted to support a mat from below, an additional support base, supports mounted thereon adapted to support the mat from above, and means for laterally moving the lower support from beneath the mat, the outer ends of the upper supports being provided with wheels and the lower support with tracks to support them.

35 19. Means for emplacing concrete mat revetments comprising a movable supporting

40 structure, means mounted thereon for suspending a unit mat freely therefrom comprising a plurality of crane arms projecting outwardly from such structure, a plurality of hoisting tackles downwardly depending from such crane arms, each of said tackles being attached to the mat, means for simultaneously manipulating said tackles to pay them out, an additional movable support base adapted to support the mat from below, and means for laterally moving the lower support from beneath the mat.

45 20. Means for emplacing concrete mat revetments comprising a movable supporting structure, means mounted thereon for suspending a unit mat freely therefrom comprising a plurality of crane arms projecting outwardly from such structure, a plurality of hoisting tackles downwardly depending from such crane arms, each of said tackles being attached to the mat, means for simultaneously manipulating said tackles to pay them out, an additional movable support base adapted to support the mat from below, and means for laterally moving the lower support from beneath the mat, said crane arms being provided with wheels, and the lower support with tracks to support them.

50 21. In an apparatus for laying a rigid revetment mat, the combination of a movable support adapted to support the mat from below, an upper support base, supports thereon for supporting the mat from above, means for laterally moving the lower support from beneath the mat, wheels on the upper support, tracks on the lower support for supporting said wheels, rollers between said tracks, and strips adapted to travel on said rollers.

55 22. An apparatus for laying protective coverings, comprising a removable support on which the covering is supported, and means for holding the covering while the support is removed and applying the covering to the surface to be protected.

60 23. An apparatus for laying revetment mats, comprising a movable float for supporting the mat from below, a movable barge lying near the said float, hoisting mechanism on said barge, the said mechanism overhanging the said float whereby the mat may be suspended and lowered to its position of rest when the said float is removed.

65 24. An apparatus for laying revetment mats, comprising a movable float for supporting the mat from below, a barge lying near the said float, hoisting mechanism on said barge overhanging the said float, and means for releasing the said mat from said mechanism.

70 25. The method of laying revetment mats which consists in supporting the mat from below on a movable support, then separat-

- ing the said support and mat, leaving the mat suspended as a unit from above and in position to be lowered on the surface to be protected, then lowering said mat on said surface. 26. The method of laying revetment mats which consists in forming and supporting the mat on a movable float, then separating the said float and mat, leaving the mat suspended as a unit from above and in position to be lowered on the surface to be protected, then lowering said mat on said surface. 27. In apparatus for laying protective slabs on the surface to be protected, the combination of a support for the slab and hoisting mechanism adapted for horizontal movement relative to each other, the said hoisting mechanism being constructed and arranged to suspend the slab while the slab and its support are relatively moved to free the slab from its support, and also to lower said slab and deposit it on the surface to be protected. 28. In apparatus for laying protective slabs on the surface to be protected, the combination of a support for the slab and hoisting mechanism adapted for horizontal movement relative to each other, the said hoisting mechanism being constructed and arranged to suspend the slab while the slab and its support are relatively moved to free the slab from its support, said hoisting mechanism being constructed and arranged to lower the slab at an angle to the horizontal and to deposit the slab on the surface to be protected. 29. In apparatus for laying protective slabs on the surface to be protected, the combination of a support for the slab and hoisting mechanism adapted for horizontal movement relative to each other, the said hoisting mechanism being constructed and arranged to suspend the slab while the slab and its support are relatively moved to free the slab from its support, the said hoisting mechanism being constructed and arranged to lower one end of the slab at greater speed than the other and cause it to descend at an angle to the horizontal and to deposit the same on the surface to be protected. 30. In apparatus for laying protective slabs on the surface to be protected, the combination of a support for the slab and hoisting mechanism adapted for horizontal movement relative to each other, the said mechanism being constructed and arranged to suspend the slab while the slab and its support are relatively moved to free the slab from its support and to lower the slab, and means for supporting one end of the slab on practically a fixed point while the other end is lowered and the slab comes to its position of rest. 31. In apparatus for laying protective slabs on the surface to be protected, the combination of a support for the slab and hoisting mechanism adapted for horizontal movement relative to each other, the said hoisting mechanism being constructed and arranged to suspend the slab while the slab and its support are relatively moved to free the slab from its support, the said hoisting mechanism comprising a series of gangs of tackle, and means for operating the said gangs together or independently of each other. 32. In apparatus for laying protective slabs on the surface to be protected, the combination of a support for the slab and hoisting mechanism adapted for horizontal movement relative to each other, the said hoisting mechanism being constructed and arranged to suspend the slab while the slab and its support are relatively moved to free the slab from its support, the said hoisting mechanism comprising a series of gangs of tackle, and means for operating the said gangs at the same speed or variable speeds. 33. In apparatus for laying protective slabs on the surface to be protected, the combination of a suitable float having a superstructure provided with hoisting mechanism, a movable support for the slab constructed and arranged to be brought adjacent to the float and moved away from the same, the said superstructure overhanging one edge of the float and the hoisting mechanism serving to suspend one end of the slab from the overhanging superstructure. 34. In apparatus for laying protective slabs on the surface to be protected, the combination of a movable support and a slab having a cradle incorporated therein, and having suspending devices, hoisting mechanism which may be detachably connected with said suspending devices for suspending the slab while its support is removed from beneath it, and then lowering the slab into its position of rest. 35. In apparatus for laying protective slabs on the surface to be protected, the combination of a movable support for a slab, a cradle consisting of a sheet of open work metal incorporated in the slab, suspending devices connected with said cradle and passing through said slab to the upper surface thereof, and hoisting mechanism which may be detachably connected with said suspending devices and serving to suspend the slab when its support is to be withdrawn from beneath it, and to lower the slab onto the surface below. 36. In apparatus for laying protective slabs on the surface to be protected, the combination of a removable slab support, a suitable float provided with hoisting mechanism for engaging the slab to suspend the slab while its support is withdrawn from beneath it and to lower the slab beneath the surface of the water, and pull cords for releasing the hoisting mechanism from the slab when the same has been deposited.

37. An apparatus for applying protective coverings, comprising a support for the covering, and means permitting the separation of the covering and said support by relative vertical movement and depositing said covering on the surface to be protected.
38. An apparatus for applying protective coverings, comprising a support for the covering, and means constructed and arranged 10 for separating the covering from said support by lifting the covering from the support to permit of the relative horizontal movement of said means and support to displace the support from beneath the covering and depositing the covering on the surface to be protected.
39. An apparatus for applying protective coverings, comprising a support for the covering, and means providing for the bodily 20 separation of said covering as a unit from said support and transferring the covering to the surface to be protected.
40. In apparatus for laying protective slabs on the surface to be protected, the combination of a movable slab-support, a float provided with slab-hoisting mechanism adapted to temporarily suspend the slab while its support is withdrawn and also to lower the slab beneath the water.
41. In apparatus for laying protective slabs on the surface to be protected, the combination of a slab-support, slab hoisting- 30 mechanism adapted to temporarily suspend the slab, said slab-support and hoisting- mechanism being adapted for horizontal

movement relative to each other to get the slab clear of its support, the said hoisting-mechanism being capable of moving with different speeds at different points thereof to lower the slab with an angular motion into 40 its position of rest.

42. In apparatus for laying protective slabs on the subaqueous surface to be protected, the combination of a slab provided upon its upper surface with multiple attaching points, slab hoisting-mechanism having multiple attaching members adapted to be releasably attached to said attaching-points of the slab and to lower the slab onto a subaqueous surface and permit it to remain 50 there during a desired test period of time, and to raise the slab subsequently.

43. The method of laying revetment mats which consists in first supporting the mat from below, then suspending it as a unit from above, then withdrawing the lower support, then lowering the mat as a unit to its position of rest.

44. The method of laying revetment mats which consists in first supporting the mat from below, then suspending it as a unit from above, then moving one in relation to the other in a horizontal direction to permit lowering the mat clear of the lower support, then lowering the mat as a unit to its position of rest.

In testimony whereof, I have signed this specification.

EDWARD M. MARKHAM.
